UNITED STATES PATENT OFFICE.

ADÉLARD F. MARTEL, OF MONTREAL, QUEBEC, CANADA, ASSIGNOR OF ONE.
FOURTH TO CHARLES A. MARTEL, OF SAME PLACE.

CAR-BRAKE.

SPECIFICATION forming part of Letters Patent No. 251,722, dated January 3, 1882.
Application filed November 1, 1881. (No model.)

To all whom it may concern:

Be it known that I, ADÉLARD F. MARTEL, of Montreal, in the Province of Quebec, Dominion of Canada, have invented certain Improvements in Car-Brakes, of which the following is a specification.

This invention is designed to render easy and certain the operation of all the brakes of a train of cars simultaneously from one point 10 and by one person, or separately from different points.

The invention consists in connecting the operating-lever of the brakes of each car with a rotary shaft or rod extending lengthwise beneath the car, and provided at its ends with a sliding or extensible coupling, by which the shaft-sections are united and caused to turn in unison, while at the same time the cars are permitted to separate or come together, as 15 usual; in providing the shaft with a universal joint at each end of the car, to permit the usual turns to be made without affecting the shaft; and in other features and details, hereinafter fully set forth and explained, the various parts 20 being constructed and arranged in the peculiar manner herein described and shown.

In the accompanying drawings, Figure 1 represents a bottom plan view of a car provided with my improvements; Fig. 2, a longitudinal 25 vertical section on the line *xx* of Fig. 1; Fig. 3, a detail view of the coupling; Figs. 4 and 5, enlarged views of the universal joint in two slightly different forms.

In their general construction and arrangement the brakes may be of ordinary construction, though I prefer to substitute for the main operating-lever, to which the brake-rods of the two trucks of each car are connected, a horizontal drum or wheel, and to provide the brake 35 rods or connections with flexible sections, composed of chain or its equivalent, to wind upon said drum. Projecting from one side of the drum or wheel is an arm, carrying a pulley at its outer end and provided with two eyes, to 40 one of which is attached one end of a spring, the other end of which is attached to the body of the car, and serves to draw back the arm and permit the brake-shoes to swing and remain normally clear of the wheels. Around 45 the pulley of the arm passes a chain or other

flexible band or cable, one end of which is permanently secured to the bottom of the car, while the other is attached to and winds upon a rotary shaft carried lengthwise beneath the car, and mounted in suitable bearings, so that 55 upon rotating the shaft the chain is wound thereon, the arm is drawn toward the shaft, and the drum is thereby caused to turn upon its pivot, drawing upon the brake-rods or connections and applying the brake-shoes to the 60 wheels.

Suitable means are provided for rotating the shaft, as will be presently explained.

Referring now to the drawings, the foregoing will be more clearly pointed out, together 65 with the details necessary thereto.

A represents the bottom of the car, and B the trucks supporting the same upon the wheels C.

D represents the brake-shoes, applied to 70 cross bars or beams E, suspended from the car-body in the usual manner. The two sets of brake shoes of each truck are caused to bear alike upon their respective wheels by means of an equalizing-lever, F, pivoted to one of the 75 beams E, and having one end connected by a rod, *a*, to the operating drum or lever G, while the other end is connected by a rod, *b*, to the other brake-shoe beam of the same truck, as shown in Figs. 1 and 2. The brake-shoes, 80 beams, and connections of both trucks are the same, a rod or connection, *a*, extending from the equalizing-lever F of each truck to the drum or wheel between the two trucks, as shown, so that upon the rotation of said drum 85 all the brakes of the car are simultaneously and equally pressed against the car-wheels.

As shown in Fig. 2, the operating-drum G is furnished with two outwardly extending arms, *c*, each carrying at its outer end a pulley, *d*, and also furnished with eyes *e*, to one of which eyes is attached one end of a spring, *f*, the other end of which is made fast to the car-body, as indicated.

H represents the main operating-shaft, carried in suitable boxes beneath the car, and to this shaft is connected one end of a chain, I, which passes about the pulley *d*, and has its other end secured to the car-body at a point between the shaft H and the arm *c*, so that as 95 100

the shaft is turned the chain is caused to wind thereon and draw the arm forward against the tension or force of the spring *f*, rotating the drum and drawing the brake shoes against the wheels, as above explained.

5 In order that the brakes of each car may be separately controlled and operated from either end of the car, as with the ordinary brake, a second chain, *J*, is attached to the arm *c* by its eye *e*, and carried thence around fixed pulleys *g*, to the usual windlasses at the ends.

10 For the purpose of permitting all the brakes of a train to be applied simultaneously and from a single point, the shaft-sections *H* of the 15 several cars are connected by means of couplings *K*, such as represented in Fig. 3, by which all the sections are caused to turn in unison, but all necessary end-play to accommodate the separation and coming together of 20 the cars is permitted. Each coupling *K* consists of two parts, *i* and *j*, formed with interlocking ends, and provided with spring-fastening devices, as shown, and arranged to slide a limited distance upon the squared end of the 25 shaft-section to which it is applied, the length of movement being limited by a chain, *k*, or by a cross-pin, shoulder, or equivalent stop.

30 The fastening devices are represented as metal spring arms or plates *l*, each rigidly secured to one part of the coupling, perforated and arranged to spring over a stud, *m*, on the other part; but other devices may be employed, if preferred.

35 From the above it will be seen that each section of the shaft *H* carries at each end a half-section or part of a coupling, *K*, so that when two cars are brought together the coupling is completed and the shaft-sections united and made virtually one shaft.

40 It is of course necessary that the shaft *H* be provided with joints, which will permit the passage of the car around bends and turns in the road without in any way interfering with the operation of the brakes. These may be 45 of either of the forms represented in Figs. 4 and 5; or any other well-known universal joint may be employed. Each shaft-section is furnished at both ends with such a joint located in rear of the shaft-coupling, as shown.

50 The manner of imparting motion to the shaft *H* may be varied; but a convenient way is that shown in the drawings, in which *L* represents a chain-wheel secured upon the shaft-section extending beneath the locomotive, and 55 *M* a drive-chain passing around said wheel and over a similar wheel on a shaft, *N*, driven by gearing *n* or from a shaft, *O*, which is furnished with a crank or hand-wheel, *P*, or which may be connected with the moving part of the 60 locomotive and furnished with a winding stop to prevent the brakes from being forced too firmly against the wheels.

The operating apparatus may be located on the tender, if desired, or elsewhere, though it is preferred to locate it in or close to the locomotive, in order that the engineer may have full control of the train at all times.

65 As the cars are run either end first, according to the position in which they are found and the direction in which they are to travel, it is 70 necessary to duplicate the shaft *H* and its connecting devices, placing one at each side, as shown in Fig. 1.

75 It is apparent that instead of chains other flexible bands may be employed, that the pulley in the head of arm *C* may be omitted and the chain passed through an eye or connected directly to the arm, that any suitable gearing may be employed to drive the shaft *H*, and that in other respects, which will readily 80 suggest themselves to the practical mechanic, the details may be modified.

I am aware that it is not new to operate the 85 brakes of a train of cars by means of rotating shafts made up of sections extending longitudinally beneath the several cars, and united by couplings and provided with universal joints, and I make no broad claim thereto.

Having thus described my invention, what I 90 claim is—

1. The coupling *K*, consisting of the parts *i* *j*, provided respectively with spring *l* and stud *m*, and adapted to move lengthwise upon the shaft sections to which they are applied.

2. In combination with the operating-shaft 95 *H*, having prismatic ends, the coupling *K* applied thereto, and the chain *k*, having its ends attached respectively to the coupling and the shaft, whereby the end movement of the coupling is limited.

3. In combination with the brakes and the drum *G*, a spring connected with said drum, as and for the purposes explained.

4. In combination with the drum or lever connected with the brakes and provided with 105 an arm, the chain *I*, made fast to the car at one end and passing around a pulley on the arm to a winding-shaft, substantially as shown.

5. The herein-described brake mechanism for cars, consisting of the ordinary brakes, 110 their operating connecting-rods, the drum *G*, spring *f*, chain *I*, and shaft *H*, combined and operating as set forth.

6. The combination, substantially as shown 115 and described, with the ordinary brakes of a car, of the drum *G*, spring *f*, chain *I*, shaft *H*, chain *J*, pulley *g*, and windlasses, all arranged to operate in the manner explained.

ADÉLARD F. MARTEL.
